COMBINED RECORD PLAYER AND RADIO-
AMPLIFIER OR SIMILAR ARTICLE

Hideo Wada, Chigasaki, Sukeyoshi Nashinoki, Yokohama, and Itsuo Kato and Tsutomu Murakami, Tokyo, Japan; said Nashinoki and Kato assignors to Matsushita Electric Industrial Co., Ltd., Osaka, Japan

Filed Sept. 14, 1970, Ser. No. 24,960

Claims priority, application Japan Mar. 13, 1970

Term of patent 14 years

Int. Cl. D14—03

U.S. Cl. D56—4

FIG. 1

FIG. 2

FIG. 3

FIG. 4

FIG. 5

FIG. 6

FIG. 1 is a left side, top and front perspective view of a combined record player and radio-amplifier or similar article, showing our new design in closed position for radio playing;

FIG. 2 is a right side, top and rear perspective view in closed position;

FIG. 3 is a front, top and right side perspective view in opened position for record playing;

FIG. 4 is a front elevational view in opened position;

FIG. 5 is a left side elevational view in opened position, the right side being substantially a mirror image thereof; and

FIG. 6 is a rear, top and left side perspective view thereof in opened position.

Portions of the drawing figures are shaded for contrast in appearance, and portions are diagonally lined to indicate transparency.

We claim:

The ornamental design for a combined record player and radio-amplifier or similar article, as shown and described.
